UNITED STATES PATENT OFFICE

ROY O. NEREIM, OF HIGHLAND PARK, ILLINOIS

DESIGN FOR A COMBINED SET OF TOILET ACCESSORY CONTAINERS AND HOLDER THEREFOR

Application filed March 18, 1932. Serial No. 43,233. Term of patent 3½ years.

To all whom it may concern:

Be it known that I, Roy O. NEREIM, a citizen of the United States, residing at Highland Park, county of Lake, and State of Illinois, have invented a new, original, and ornamental Design for a Combined Set of Toilet Accessory Containers and Holder Therefor, of which the following is a specification, reference being had to the accompanying drawing, forming a part thereof.

In the drawing, Fig. 1 is a perspective view of a combined set of toilet accessory containers and holder therefor constituting my design.

Fig. 2 is a similar perspective view to a somewhat reduced scale which is included for

the purpose of showing how the article looks when in its closed position.

The form and arrangement of the component parts, elements and their carriage is a dominant feature of my design. The external aspect of the design as shown in Fig. 2 is conventional for cases for other purposes.

I claim:

The ornamental design for a combined set of toilet accessory containers and holder therefor as shown and described.

In witness whereof, I hereunto set my name this 7th day of March, 1932, at Chicago, Illinois.

ROY O. NEREIM.
